Ernest A. Schaefer

UNITED STATES PATENT OFFICE.

ERNEST A. LE SUEUR, OF OTTAWA, ONTARIO, CANADA.

ELECTROLYTIC CELL.

1,331,571.

Specification of Letters Patent. Patented Feb. 24, 1920.

Application filed January 25, 1919. Serial No. 273,151.

To all whom it may concern:

Be it known that I, ERNEST A. LE SUEUR, a subject of the King of Great Britain, residing at Ottawa, in the county of Carleton 5 and Province of Ontario, Canada, have invented certain new and useful Improvements in Electrolytic Cells, of which the following is a specification.

My invention has reference to cells employing thin sheets of platinum or the like for the anodes, and its object is to provide improved means, in the particulars of effectiveness, simplicity and small repair charges, for delivering heavy commercial currents to 10 said sheets beneath the surface of the electrolyte. My said invention will be fully understood by reference to the accompanying drawings in which Figure 1 shows a plan of a set of electrodes and attachments; Fig. 2 an end elevation section, on the line A—B of Fig. 1, of the apparatus of Fig. 1 15 with the exception of the parts of Figs. 3 and 4, and including a view of the containing vessel and electrolyte and showing in vertical central section a protective sleeve 25 on the anode lead not shown in Fig. 1; Fig. 3 shows a side elevation of a set of inner cathode members; Fig. 4 shows a central side elevation section view of the anode and 30 sheath.

With more particular reference to the drawings, 1 is an anodic stem, preferably of copper, cased in the chemically resistant sheath 11, of platinum or the like; 2 is the 35 main cathodic lead, also preferably of copper; 3, 3' and 3'' are thin anodic sheets of platinum or the like; 4, 4' are pieces of insulating material, preferably plastic, as rubber; 5, 5' are substantially rigid pieces which 40 may be either insulating or conducting; 6 is a flexible metallic casing, of sheet steel or the like; 7, 7' are self-contained sets of inner cathode members; 8 is a yoke, conveniently of cast iron, adapted, by means of the screw 45 81, to clamp all the preceding parts together; 9, 9' are insulating separating pieces; 10 is an (oblong) containing vessel of any suitable material; 20 is the electrolyte; 12, Fig. 2, is a (preferably insulating) tube; 50 13, of insulating material, constitutes a tight joint between the parts 11 and 12 and may, for instance, be of rubber or any suitable cement; 12 and 13 may be combined into a single piece, for instance of rubber, and 55 the whole may, if desired, make a close fit on the stem and sheath; 21 is a stiff piece

as of steel, adapted to distribute the pressure of the yoke 8 on one side of the assembly the same as the piece 2 does on the other; 61 is wire cloth at the bottom of the 60 piece 6; 71 is a metallic strap adapted to being bolted or otherwise attached to the casing 6. The cathode surfaces as shown herein are constituted by the cathodic lead 2, the flexible metallic casing 6, the two sets 65 of removable members 7, and the parts 8, 21, 61, 71 and 81; also, in case same are made conducting instead of insulating, the pieces 5, 5'.

The points of the pieces 9 fit into holes 70 in the wire cloth 61 and are therefore not readily disturbed. The casing 11 is preferably of much thicker metal than are the sheets 3, 3' and 3'',—convenient thicknesses in the two cases being about 0.002" and 75 0.0008" respectively. The said sheets are illustrated as projecting below the bottom of the stem 1 and sheath 11; this is with a view to economizing on the resistant metal required for said sheath, the latter may, however, be carried to any desired depth. The sheets are shown parallel but they need not be so in order to conform with the spirit of my invention. Said sheets may be bonded to the sheath 11, as, for instance, by welding; but 80 the method I prefer for securing contact between said sheets and said sheath is to press the former against said sheath by superposing upon them the piece 4. I have shown three pairs of double sheets (and the 85 90 appropriate number of divisions of the parts 7 to correspond) but I do not wish to limit myself to this number either as an upper or a lower limit. The member 1 and the sheath 11 may obviously be of any convenient shape, 95 and the same applies to other portions of the apparatus. I may employ a plurality of stems 1 and sheaths 11 but I much prefer the single stem. The parts 12 and 13 may be omitted and the protective sheath 11 carried higher up on the stem 1; or the said sheath may reach above the surface of the electrolyte and the pieces 12 and 13 be still used if even only to protect the stem 1 from corrosion due to the creeping of solution up 100 over the top of the sheath 11. The bottom 61 may obviously be perforated in other ways than by making it of wire cloth. There is considerable advantage in the use of the self-contained sets of cathode members 7 110 which can be set into place after the rest of the electrode assembly has been made,

thus greatly simplifying an otherwise troublesome operation.

In speaking in the claims of "resistant" metal I mean resistant to chemical attack.

5 I claim:

1. In an electrolytic cell an anode having a conducting stem protected by a conducting sheath of resistant metal and sheets of resistant metal in contact with the latter

10 beneath the electrolyte.

2. In an electrolytic cell an anode having a conducting stem protected by a resistant conducting sheath and sheets of resistant metal, in contact with the latter, extending

15 laterally and downwardly from same.

3. In an electrolytic cell an anode having a conducting stem protected by a conducting sheath of resistant metal and sheets of resistant metal clamped against opposite

20 sides of the latter.

4. In an electrolytic cell an anode having a conducting stem protected by a conducting sheath of resistant metal and sheets of resistant metal clamped against opposite

25 sides of the latter and extending laterally

and downwardly from same.

5. In an electrolytic cell an anode having a conducting stem protected by a conducting sheath of resistant metal and sheets of

30 resistant metal in electrical contact with the

latter, said sheath having a thickness mate-

rially greater than said sheets.

6. In an electrolytic cell an anode having

a conducting stem protected by a conduct-

35 ing sheath of resistant metal and a plurality

of superposed sheets of resistant metal

clamped against each of two opposite sides

of said sheath.

7. In an electrolytic cell an anode having

40 a conducting stem protected by a conduct-

ing sheath of resistant metal and one or

more sheets of resistant metal clamped

against said sheath by an insulating mem-

ber.

45 8. In an electrolytic cell an anode having

a conducting stem protected by a conduct-

ing sheath of resistant metal and one or

more sheets of resistant metal clamped

against said sheath by a plastic insulator

backed by a substantially rigid member. 50

9. In an electrolytic cell an anode having

a conducting stem protected by a conduct-

ing sheath of resistant metal and sheets of

resistant metal clamped against opposite

sides of same by insulating material. 55

10. In an electrolytic cell an anode having

a conducting stem and metallic sheets pressed

into contact with opposite sides of same by

insulating pieces held in a flexible casing. 60

11. In an electrolytic cell an anode having

a conducting stem and metallic sheets pressed

into contact with opposite sides of same by

insulating pieces held in a flexible metallic

casing and clamping arrangements applied

to said casing. 65

12. An electrolytic cell having an anode

possessing a plurality of anodic sheets con-

tained in a cathodic casing and one or more

subsidiary cathode members adapted to be

set into place and bonded to said casing 70

after the parts previously mentioned have

been assembled.

13. In an electrolytic cell an anode having

a conducting stem with its lower portion

protected by a resistant conducting sheath 75

in electrical contact with it and a further

portion higher up protected by a sleeve, in-

sulated from said stem, or of insulating ma-

terial.

14. In an electrolytic cell an anode having

a conducting stem with its lower portion

protected by a resistant conducting sheath

and an insulated or insulating sleeve, over-

lapping the upper portion of said conduct-

ing sheath and making a tight joint there-

85 with, which carries the protection of said

stem higher than does said sheath.

15. In an electrolytic cell a set of posi-

tive and negative electrodes contained in a

metallic cathodic casing with perforated 90

bottom.

ERNEST A. LE SUEUR.
